REFRIGERATING APPARATUS

Filed Oct. 2, 1937

UNITED STATES PATENT OFFICE

2,161,912

REFRIGERATING APPARATUS

Hursle E. Cossin, Detroit, Mich., assignor to Nash-Kelvinator Corporation, Detroit, Mich., a corporation of Maryland

Application October 2, 1937, Serial No. 166,954

1 Claim. (Cl. 211—143)

My invention pertains to a refrigerator shelving arrangement and more particularly to a slideable drawer assembly and shelf supporting rack for household refrigerators.

5 It is an object of my invention to provide in a refrigerator an arrangement of open work vertically spaced shelves and slideable drawers for storing food articles exposed to the freely circulating cold air in a refrigerator cabinet whereby the 10 desired degree of refrigeration is conveniently obtained for different food articles.

It is also an object of my invention to provide a simple rigid open work rack for supporting a plurality of slideable open work drawers vertically 15 between the evaporator and a side wall of a refrigerator cabinet.

A further object of my invention is to provide a refrigerator sliding drawer assembly having spaced guide rails slidably disposed between respective pairs of guide rods for slideably supporting and guiding drawers in a rack.

The novel features that I consider characteristic of my invention are set forth with particularity in the appended claim. The invention itself, however, both as to its organization and 25 its method of operation, together with additional objects and advantages thereof, will best be understood from the following description of a specific embodiment, when read in connection 30 with the accompanying drawing, in which:

Fig. 1 is a perspective view illustrating a refrigerator cabinet with the door opened to show my improved shelving arrangement therein;

Fig. 2 is an enlarged perspective view of the 35 open work rack provided for supporting a plurality of slideable drawers and also the large horizontal shelves in the cabinet.

Fig. 3 is a side elevational view of a refrigerator partly sectioned on lines 3—3 of Fig. 1 to show 40 the sliding drawer assembly;

Fig. 4 is an enlarged sectional view on line 4—4 of Fig. 3; and

Fig. 5 is an enlarged perspective view showing 45 one of the sliding drawers adapted to slide into the rigid open work rack.

Referring more specifically to Fig. 1 of the drawing, the apparatus comprises a heat insulating cabinet 1 for enclosing a food storage space 3 having an open doorway at one side 50 which is closed by a heat insulating door 5 hinged along one of the vertical edges thereof in the usual manner. A cooling evaporator 7 is suspended from the middle of the upper wall of the food storage compartment in spaced relation 55 from the side walls for cooling the air as it circu-

lates therein. The evaporator 7 is supplied with liquid refrigerant from any suitable refrigerant condensing unit which may be mounted in a machine compartment provided in the lower portion of the refrigerator cabinet in the usual 5 manner.

In accordance with my invention, I provide a rigid open work rack 9 of simple open work construction. As shown in Fig. 2, the rack 9 comprises four vertically disposed corner rods 11 10 which are secured at the outer corners of rectangular rod-like frames 13 in any suitable manner, as by welding for example. The two uppermost frames 13 are suitably spaced to provide a shelf, the bottom of which is defined by a pair of spaced 15 rods 15 extending longitudinally between the short ends of the frame 13 to which it is secured and having upwardly turned end portions 17 secured to the ends of the uppermost one of the rectangular frame members 13.

The remainder of the rectangular frame members 13 are suitably spaced vertically between the corner rods 11 for supporting slideable drawers 18. For this purpose, each of the drawer receiving frames 13 is provided with a pair of spaced 25 guide rails 19, the ends of which are secured to the short end portions of the rectangular frames 13 in any suitable manner, as by welding. Side rods 21 are connected along the sides of the rack between the corner rods 11 at suitable spaced 30 portions between the rectangular frame 13 to guide the movements of the slideable drawers 18 thereon. The rods 21 also serve to improve the rigidity of the completely assembled rack.

A pair of side bars 23 are secured vertically 35 on one side of the vertical rack 9 as by spot welding to the adjacent sides of the rectangular frames 13. The vertical bars 23 are provided with up-turned hooks 25 which project externally therefrom for receiving and supporting the 40 edges of the large horizontal shelves in the refrigerator cabinet. The rigid open work construction rack 9 thus provides a plurality of vertically spaced drawer supporting guides and an open work shelf at the top thereof for supporting small articles such as oranges, apples, eggs and the like.

As shown in Fig. 1, the rigid drawer assembly 50 rack 9 is of a suitable size for mounting vertically in the food storage compartment adjacent one side wall thereof and the upper portion of the rack is disposed between the evaporator cooling element 7 and the side wall whereby a wide 55 variety of refrigerating temperatures is conveniently provided for storing different food articles 55

therein, while permitting the cold refrigerated air to circulate freely therethrough. The rack 9 is conveniently slipped into place in the storage compartment of the refrigerator and the 5 horizontally disposed shelves 27 are thereafter hooked upon the supporting hooks 25 which project from one side of the rack. The wall of the food storage compartment, adjacent the vertical drawer supporting rack 9, may be provided with 10 resilient hooks 28 for resiliently clasping the adjacent side rods 21 of the rack whereby the rack is secured in the refrigerator cabinet, as shown in Fig. 4.

The drawers 18, which are slidably disposed 15 within the vertical rack, comprise each a front plate 31 provided with a handle portion 33 struck out therefrom. From the front plate 31, a rod-like rectangular member 35 projects rearwardly, and depending therefrom are vertically disposed 20 rectangular members 37 which are joined by elongated rod-like members 39 which are spaced under and parallel to the sides of the rectangular member 35. The parallel spaced members 39 may be secured to the rectangular members 37 25 and the front plate 35 in any suitable manner, as by welding for example. For slidably supporting and guiding the drawer in its movements upon the spaced guide rails 19 of the rack 9, each drawer, is provided with two pairs of spaced 30 guide rods 41 secured longitudinally under members 37, as shown more clearly in Fig. 4. Each pair of spaced guide rods 41 fits over and slides along one of the guide rails 19 supported on the rack. In this manner each drawer is rigidly supported and accurately guided for free movement 35 in and out of the vertical supporting rack 9.

It will be seen that I have provided an improved

rack assembly of slideable drawers spaced vertically for storing food articles whereby the various desired degrees of refrigeration are conveniently available for different food articles, whilst providing convenient storage space for small articles and supporting means for the large shelves in the cabinet.

Aside from the specific embodiment of the invention herein shown and described, it will be understood that numerous details of the construction may be altered or omitted without departing from the spirit and scope of the invention as disclosed and claimed, and that I do not desire to limit the invention to the exact construction herein set forth.

15
I claim:

In a rack for refrigerators the combination of a wire frame including four vertically extending wire corner members, open work shelf members vertically spaced between and secured to said wire corner members, two horizontally positioned wire members cooperating with each of said wire corner members and being vertically spaced in parallel relation adjacent the upper ends of said corner members and secured thereto, a plurality 20 of U-shaped wire members having longitudinally extending portions arranged on a horizontal plane and extending from one end of the rack to the other and vertically extending portions between and cooperating with said two horizontally 25 positioned wire members to provide a basketlike shelf for storing small food articles and a pair of side bars secured vertically to certain of said shelves to provide a rigid open work construction and having provisions for receiving and support- 30 ing additional shelf structures.
